UNITED STATES PATENT OFFICE.

JOHN L. SOMMER, OF NEWARK, NEW JERSEY.

DESIGN FOR A HANDLE FOR PAPER-KNIVES OR SIMILAR ARTICLES.

SPECIFICATION forming part of Design No. 33,679, dated December 11, 1900.

Application filed July 25, 1900. Serial No. 24,821. Term of patent 7 years

To all whom it may concern:

Be it known that I, JOHN L. SOMMER, a citizen of the United States, and a resident of Newark, in the county of Essex and State of New Jersey, have invented and produced a new and original Design for Handles of Paper-Knives or Similar Articles, of which the following is a specification.

This invention relates to a new design for the handles of paper-knives and other small articles or implements of which the handles are commonly formed integral with the blade or shank.

The accompanying drawings illustrate such a handle formed with the present design.

Figure 1 is a face view, and Fig. 2 an edge view, of the same.

The body of the handle consists of a flat blade divided by transverse ribs *r* into a plain central or intermediate portion *a*, having parallel edges and end sections *b* and *c*, the edges of each of which are rounded inwardly at their farther ends and whose flat faces are flared to the point of junction with

the adjacent cylindrical portions *d* *e*, respectively.

Between the blade or shank of the implement (indicated in the drawings in dotted lines) and the portion *d* of the handle is a circular bead *g*, the handle being reduced on the side of said bead adjacent the portion *d* to form a contracted neck *h*. The opposite extremity of the handle terminates in a ball or knob *i*, the connecting part intermediate the same and the portion *c* being reduced to form a small notch or groove *j*. The flattened portions *b* and *c* are shown provided each with an ornamental pattern.

Having thus set forth the nature of the invention, what I claim herein, and desire to secure by Letters Patent, is—

The design for a handle for paper-knives or similar articles substantially as herein shown and described.

JOHN L. SOMMER.
